(No Model.)

W. BISHOP.

PUMP WATER CLOSET.

No. 378,353.

Patented Feb. 21, 1888.

UNITED STATES PATENT OFFICE.

WILLIAM BISHOP, OF BROOKLYN, NEW YORK.

PUMP WATER-CLOSET.

SPECIFICATION forming part of Letters Patent No. 378,353, dated February 21, 1888.

Application filed July 18, 1887. Serial No. 244,604. (No model.)

To all whom it may concern:

Be it known that I, WILLIAM BISHOP, of Brooklyn, Kings county, New York, have invented certain new and useful Improvements 5 in Pump Water-Closets, of which the following is a specification.

My invention relates to that class of water-closets, usually called "marine" or "pump" water-closets, used on board ship, in which a 10 suction-pump withdraws the contents of the bowl and discharges it into the sea, while a second pump connected with a water-supply injects water to flush the bowl, both pumps being operated by the same hand-lever mounted 15 alongside the seat of the closet.

In some closets of this class the soil-pump and the water-pump are combined in one cylinder and piston, the part below the piston serving as the soil-pump, while the part above 20 the piston acts as the water-pump, so that an upstroke of the piston will withdraw the contents from the bowl and inject a flush of water into the bowl, while the downstroke discharges the soil into the sea while a fresh charge of 25 water is drawn into the top of the cylinder. While this construction has some advantage in embodying the two pumps in one cylinder and piston, yet the plan has a disadvantage in not enabling the bowl to be pumped out in case 30 it becomes flooded by a leakage from the sea, for while every stroke of the pump will withdraw some of the contents of the bowl it will also inject water therein, and thus prevent the bowl from being quickly emptied when once 35 flooded.

In another plan of construction to which my invention belongs—such as shown in my former patents, No. 289,210, of November 27, 1883, and No. 205,036, of June 18, 1878—a 40 separate soil-pump and water-pump are used, the water-pump being much smaller than the soil-pump, but both operated by the same hand-lever. In case the bowl becomes flooded in this form of closet it may be readily pumped 45 out by disconnecting the water-pump from the hand-lever, allowing the soil-pump alone to act.

In my former closets the idle air-chamber in the top of the soil-pump above the piston was 50 connected by an air-vent pipe with the bowl, so as to vent the cylinder at the top and allow freedom of motion to its piston, while the discharge-

pipe of the water-pump connected directly to the bowl. Now, in my present improvement I employ the same pipe connecting the bowl 55 with the top of the soil-pump; but in addition I connect the discharge-pipe of the water-pump directly to the upper chamber of the soil-pump, so that the water-pump first discharges its water into the soil-pump above 60 the piston, and from thence it flows into the bowl through the air-pipe connecting the soil-pump and bowl. In this way the water keeps the top of the soil-pump cleansed and its piston better lubricated and sealed, and besides 65 this the volume of air drawn in and ejected from the upper part of the soil-pump by the motion of the piston flows intermittently with the water from the water-pump through the vent-pipe, so that the water is thus injected 70 into the bowl with much greater energy, due to the elastic projecting effect of the air, so that the water is ejected and distributed in the bowl with a much better flushing and cleansing effect that when it is ejected quietly directly 75 from the water-pump.

My present invention therefore consists in the feature above explained, as hereinabove fully set forth and claimed.

The figure in the annexed drawing presents 80 a sectional elevation of my improved marine closet.

In the drawing, *a* indicates the bowl or basin of the closet; *b*, the soil-pump cylinder; *c*, the piston thereof; *d*, the cylinder of the water-pump, and *e* the piston thereof. *f* is the pipe which connects the base of the bowl with the base of the soil-pump, opening into the side of the soil-pump, as shown, and is provided with a suction-valve, *g*, which opens toward 90 or into the pump and closes in the reverse direction, as usual. *h* is the discharge-pipe, which opens from the base of the soil-pump and discharges into the sea through the side of the ship, as usual, having an outwardly-opening check-valve at *i*, in the ordinary way. *k* is a water-supply pipe which leads from a supply of water to the bottom of the water-pump *d*, and *l* is an inwardly-opening or suction valve in the bottom of the pump. *m* is 100 an outwardly or upwardly opening valve in the piston of the water-pump, all of the usual character.

The soil-piston *c* is solid or without valves,

as usual, but is provided with the usual packing to insure a tight fit in the cylinder, as illustrated. The piston-rods of both pumps pass through stuffing-boxes in the tops of their cylinders, and connect, as usual, to an operating hand-lever, *n*, the fulcrum end of which is pivoted to the upper end of an upright link, *o*, the lower end of which is jointed to a lug on the rim of the bowl, as illustrated.

10 *r* indicates the water-discharge pipe of the water-pump.

The soil-pump, as will be noted, is much larger than the water-pump; but the stroke of the water-pump is greater, as it is connected 15 with the pumping-lever *n* at a longer distance from the fulcrum; but the displacement of the soil-pump is greater than that of the water-pump, so that the soil-pump can always withdraw the contents of the bowl faster than the 20 water-pump could fill the same, as is usual in these closets, as will be understood. Now, the air-tight chamber in the top of the soil-pump above the piston is connected by the vent-pipe *p* with the top of the bowl *a*, said vent-pipe opening into the bowl tangentially, in 25 the usual way in which water-flushing pipes open into water-closet bowls, as is illustrated and will be understood. This pipe thus allows an air-vent to the top of the soil-pump to allow 30 the piston to work freely without being air-bound, as will be readily comprehended, as set forth in my former patent, No. 289,210; but this pipe in my present invention also serves the additional function of a flushing-pipe, as 35 through it also the water is discharged to flush the bowl, for it will be noted that the water-discharge pipe *r* of the pump, instead of being connected directly with the bowl, as heretofore, connects to the top of the soil- 40 pump into the same air space or chamber into which the vent-pipe *p* opens. Consequently, when the pumps are operated by movement of the hand-lever, the soil and water will be withdrawn from the bowl by the movements 45 of the soil-piston, while clean water will be discharged by the water-pump into the top of the soil-pump, from whence it will flow with the air displaced by the upstroke of the soil-pump through the pipe *p* with energetic spurts 50 into the bowl, thus cleansing and flushing the same effectually. The water being thus discharged first into the soil-pump will keep the same cleansed and its sides wet and lubricated, and will act as a water seal and packing 55 on the piston, insuring an easier and tighter action of the piston and rendering the packing more durable, besides preventing the formation of any dry or incrusted deposits, as are likely to form with the previous construction. 60 The soil-pump, being thus kept clean by the

constant flow of water into the same, will prevent the air which is drawn into and discharged from the cylinder from being tainted thereby, and from thus causing an unpleasant smell to arise from the closet when the pump 65 is operated, as is likely to happen with the old construction. Besides, this air, being discharged with the water and being partly compressed in bubbles or masses between masses of water in the pipe *p*, will cause the water to 70 be ejected with much greater force in the bowl and in a manner which is much more effective for cleansing the bowl than would be a smooth solid stream of water discharged directly from the water-pump, as heretofore. 75

It will be noted that in case the bowl should ever become flooded by leakage through the check-valves from the sea it can be readily pumped out by detaching the piston-rod of the water-pump from the pump-lever and operating the soil-pump alone until the bowl is 80 emptied, when the water-pump can be connected as before. 85

It will be noted that the upper part of the soil-pump, into which the water-pipe *r* discharges, is practically an air-pump, and that this air-pump discharges its jets of air, together with water supplied from the water-pump, through the pipe *p* into the bowl, which is, in fact, a new mode of flushing and cleansing 90 a closet.

What I claim is—

1. The combination, with a water-closet bowl, of an air-pump and a water-pump, the water-pump being arranged to discharge into 95 the air-pump, while the air-pump discharges into the bowl, substantially as herein shown and described.

2. The combination, in a pump water-closet, with the bowl and separate soil and water 100 pumps, of a water-discharge pipe or duct extending from the water-pump to the idle-chamber of the soil-pump cylinder above the piston thereof, and a second pipe or duct extending from said chamber to the bowl, substantially 105 as and for the purpose set forth.

3. An improved marine closet formed by the combination of the bowl *a*, pumps *c b* and *d e* *m l*, having open connection with each other and with the bowl, operating device *n*, operating said pumps, pipes *f h*, leading from the bowl to the pump *c b*, and from thence to the discharge-outlet, and the pipes *r* and *p*, connecting the pumps and the bowl, respectively, substantially as set forth. 110

WILLIAM BISHOP.
